UNITED STATES PATENT OFFICE.

LOUIS J. ANSHEN, OF PROVIDENCE, RHODE ISLAND.

DESIGN FOR A CLASP OR SIMILAR ARTICLE.

Application filed November 19, 1923. Serial No. 7,817. Term of patent 3½ years.

To all whom it may concern:

Be it known that I, LOUIS J. ANSHEN, a citizen of the United States, residing at Providence, R. I., have invented a new, original, and ornamental Design for Clasps or Similar Article, of which the following is a specification, reference being had to the accompanying drawing, forming a part thereof.

Figure 1 is a front view of a clasp body showing my new design.

Figure 2 is an edge view of the clasp body. The ten plain areas in Figure 1 which are completely surrounded by beading, indicate holes through the front of the clasp.

I claim:

The ornamental design for a clasp or similar article, as shown.

LOUIS J. ANSHEN.
